APPARATUS FOR JOINING WIRES AND THE
LIKE BY FUSIONGilbert Gilliver, London, England, assignor to
Standard Telephones and Cables Limited, Lon-
don, England, a British companyApplication March 5, 1945, Serial No. 581,122
In Great Britain March 20, 1944

9 Claims. (Cl. 219—4)

1

This invention relates to improvements in apparatus for the joining of wires and the like by fusion, and has for its main object to provide an improved construction of hand tool employing the principles embodied in British application No. 13849/42.

The tool may consist of two castings or mouldings which are clamped together to form a handle. These parts are recessed and shaped to provide accommodation for two side plates at the top, a moulded trigger, pawl, and restoring spring, in the centre, a contact spring, and the connecting cable at the bottom.

One side plate insulated from the handle has an aperture through which the wires to be jointed are passed and pressed against a carbon electrode carried on a spring support housed by the other side plate, the wires being pressed in until the carbon block is pressed back to the maximum extent. The trigger, which carries a clamping spring, a quick release pawl for the contact spring housed in the lower part of the handle, a contact screw and a restoring spring is pivoted on a pin which is located by bearing holes in the two parts of the handle. When the trigger is depressed it first of all clamps the inserted wires between the clamping spring and an anvil provided at one side of the aperture of the side plate, and then by means of the pawl releases the movable contact spring which makes contact with the contact screw in the trigger, completes the circuit and fuses the ends of the wires pressed against the carbon block. This automatically opens the circuit, the trigger is released and the wires, now beaded by the fuse weld, are withdrawn.

In the accompanying drawings:

Figs. 1 and 2 are external side and front views of the assembled tool;

Fig. 3 is a front view with one half of the handle removed; and

Fig. 4 is a side view as Fig. 1, but with a portion in section to show the method of terminating one wire of the cable.

Figs. 1 and 2 show views of the completely assembled tool, the two castings or mouldings 1, 2, are clamped and held together by the screws and nuts at 3, 4 and 5. Screws and nuts 4 and 5 also secure the two side plates 6 and 7.

Side plate 6 has an aperture 8 for the insertion of the wires to be jointed, and these are pressed against the anvil 9, by the clamping spring 10, which is carried on the trigger 11. Side plate 6 is insulated from the handle by plate 33 and bushes 34.

Side plate 7 clamps the spring 12, carrying the

2

carbon electrode 13, which is so mounted on the spring as to be readily replaceable. The two parts 1 and 2 also clamp the connecting cable 14.

A window 15, is retained in position by the side plates 6 and 7 to prevent splashes from the welding operation from reaching the operator.

In Fig. 3 handle part 1 has been removed to show the internal arrangement.

The moulded trigger 11 is pivoted by pin 16, which also pivots the pawl 17 of insulating material for operating the contact spring 18. The trigger 11 carries the clamping spring 10 secured by the contact screw 19, and has a slot 20, which in conjunction with pin 21 limits the movement of the trigger 11, which is restored by spring 22, located by pin 23, spring 22 being retained in position when the two halves of the handle are clamped together.

Side plates 6 and 7 have suitably shaped wire 20 guides 24 welded to them to accommodate the window 15; and anvil 9 is secured to side plate 6 by the screws 25, 26.

Spring 18 is secured to and insulated from the handle 2 by screws 27, 28, and insulating plates 29.

Spring 18 has a bush 30 riveted to it, which is drilled to take one lead from the cable 14, clamped in the bush by grub screw 31; the other wire from the cable 14 is terminated in a circular clamping 30 washer 32 and clamped between bosses on the two halves of the handle by screw and nut 3 as shown in Fig. 4.

Carbon electrode 13 may be slidably mounted on the spring 12 so that it can be moved up and down or reversed, or readily replaced, without disassembling the tool.

Anvil 9 may be replaced in position by removing the screws 25, 26.

Other working parts, viz: side plates 6 and 40 7 and window 15, may be replaced by removing screws and nuts 4 and 5.

Finally, contact screw 19, contact spring 18, pawl 17, trigger 11, restoring spring 22, and cable 14 may be replaced by removing screws 3, 4 and 5.

In operation, the wires to be jointed, are cleaned, preferably twisted together, the ends cut parallel, if necessary, inserted through aperture 8 and pressed against carbon electrode 13, the holding spring 12 for the carbon electrode 50 being pressed back against the side plate 7. Trigger 11 is then compressed, the clamping spring 10 first clamps the wires against the anvil 9 and then the pawl 17 releases spring 18, the contacts make, the circuit is completed, a bead is formed on the wires at or near the surface of

the carbon electrode and this automatically opens the circuit. The trigger is then released and the wires withdrawn.

It will be observed that the aperture 8 is rhomboid shaped so that the wires are directed positively towards the inclined anvil by the action of the clamping spring 10. In the example described the handle parts 1 and 2 are of metal and the circuit includes these parts to which the carbon electrode 13 is electrically connected through spring 12 whereas the remainder of the circuit is through spring 18 contact 19 clamping spring 10 and anvil 9 which are suitably insulated from the metal handle parts.

The term "wires and the like" as used in this specification is intended to cover circular wires or flat strips such as terminal tags or the like and the wires may be stranded in the form of flex. The apparatus according to this invention is particularly advantageous in joining fairly thick wires, for example, 20-30 S. W. G. or for joining such wires to terminal tags or strips.

What is claimed is:

1. A hand tool for joining wire and the like by fusion comprising in combination a casing forming a handle, a pair of plates mounted on said casing in spaced relation and insulated one from the other, a spring mounted carbon electrode located within the space between said plates, said electrode being adjacent one of said plates and movable towards and away from an aperture in the other plate, a trigger lever pivotally supported in said casing, a clamping spring on said trigger lever positioned to move across said aperture and means for connecting an electric circuit to said electrode and said clamping spring.

2. A hand tool according to claim 1 wherein a boss or projection is provided on the plate along one edge of the aperture to provide an anvil for co-operation with said clamping spring.

3. A hand tool according to claim 1 wherein the trigger lever is operatively connected with a pawl or cam arranged to operate a switch contact spring in the casing, said switch contact spring being arranged to co-operate with a contact connected with the clamping spring.

4. A hand tool according to claim 1 wherein

the carbon electrode is slidably mounted on a spring supporting member secured between the adjacent plate and the casing.

5. A hand tool according to claim 1 wherein a protective shield in the form of a window is provided between said plates.

6. A hand tool according to claim 1 wherein the casing comprises two moulded or cast parts between which the trigger lever and associated parts are assembled and the plates are secured at one end of said parts.

7. A hand tool for joining wires and the like by fusion comprising two casing portions supporting opposed side plates insulated from each other, a trigger pivotally supported on the casing portions, a clamping spring movable with the trigger, an electrode supported by one of the side plates, an anvil supported by the other of said plates and positioned to co-act with the clamping spring in clamping of the work, a contact mounted on the trigger and electrically connected to the clamping spring, a resilient contact supported in position for engagement with the trigger contact, a pawl movable with the trigger and engaged by the resilient contact to time the closing of the latter subsequent to the clamping of the work and means for connecting an electric circuit to said electrode and to said resilient contact.

8. A hand tool according to claim 7 wherein the electrode is yieldingly supported to be movable toward the opposite plate.

9. A hand tool according to claim 7 wherein the electrode is a carbon electrode and is yieldingly supported to be movable toward the opposite plate and wherein the latter is formed with an opening for the reception of the work in position to engage the anvil.
